UNITED STATES PATENT OFFICE.

JOHN ST. AMAND, OF BROCKTON, MASSACHUSETTS, ASSIGNOR TO WILLIAM B. ARNOLD, OF NORTH ABINGTON, MASSACHUSETTS.

HINGE.

SPECIFICATION forming part of Letters Patent No. 731,389, dated June 16, 1903.

Application filed December 10, 1897. Serial No. 661,358. (No model.)

To all whom it may concern:

Be it known that I, JOHN ST. AMAND, a subject of the Queen of Great Britain, residing at Brockton, county of Plymouth, State of Massachusetts, have invented an Improvement in Hinges, of which the following description, in connection with the accompanying drawings, is a specification, like letters on the drawings representing like parts.

10 My invention is an improvement in hinges, having for its object the provision of a hinge offering great resistance to longitudinal strains—that is, to strains lengthwise of the leaves of the hinge and transverse to the 15 pintle thereof.

My hinge is primarily intended to be embedded in the wood or other material of the parts joined thereby, and at each end of the leaves of the hinge I provide outturned 20 flanges which present a sharp angle, preferably a right angle, at their junction with the leaf or leaves composing that part of the hinge, this sharp angle preventing any wedging action and holding into the wood with a 25 firm and extremely tenacious grip.

In the accompanying drawings, Figure 1 shows in perspective a preferred embodiment of my invention. Figs. 2 and 3 are side elevations of modified forms of my invention, 30 and Fig. 4 is a sectional view illustrating a manner of using my invention.

Referring to the drawings, the general shape and arrangement of the hinge, herein shown as comprising leaves a' , joined by a 35 pintle a^2 , may be of any desired or preferred pattern convenient for the special purpose to which the hinge may be put or adapted. The ends of the leaves are provided with outturned flanges a^3 , and preferably there will 40 be four of these flanges, two extending in opposite directions at each end of the hinge, although it will be understood that one main object of my invention is to provide a sharp definite corner at a^4 , and therefore the specific location of the flanges may be varied 45 considerably as well as their extent and particular shape may be varied.

In Figs. 1, 3, and 4 I have shown the flanges a^3 as projecting perpendicularly from the 50 body or leaves of the hinge and in Fig. 2 I

have shown the flanges a^3 as projecting backwardly over the leaves of the hinge, so as to form an acute angle therewith, the object of this modification of my invention being to cause the hinge itself to hug into the wood 55 at each side thereof under any longitudinally-pulling strain.

By having the flanges a^3 extended from the body or leaves of the hinge at a sharp angle of ninety degrees or less therewith they offer 60 a very powerful resistance to longitudinal strains, said longitudinal pull being distributed over the whole section of the material included by the flanges, all the pulling strain coming directly in longitudinal line with the 65 hinge without causing any lateral movement or splitting tendency.

Referring to Fig. 3, it will be seen that I have provided a further strengthening feature in the form of a lateral offset a^5 , preferably projecting rearwardly therefrom, which prevents the outer end of the flange a^3 from being bent and in the form shown absolutely prevents any backward deflection thereof under any strains, and preferably, also, I 75 provide a depending lip or flange a^6 , which forms, with the opposite flange a^3 and the offset a^5 , a box-like rib or projection on the body of the hinge; and in case these are used in opposite pairs, as herein shown, the two 80 thereof constituting the pair coöperate as a single T-shaped head or double shoulder for the hinge.

My invention is intended to include the use of a single flange a^3 or of opposite flanges, as 85 is herein shown, and it includes the forming of these by oppositely bending, casting, or otherwise shaping the material constituting the hinge, or, if preferred, the hinge may be cast or otherwise formed with both of the opposite flanges a^3 formed in one integral T-head, and this may be solid, or hollow, substantially as shown in Fig. 3. In the latter case I prefer to use a key or filling-block or pin a^7 , as shown in Fig. 4, which wedges or 90 holds the parts of the hinge which form the projections or ribs thereof out solidly and firmly into the wood or other material b in which the hinge is embedded.

I disclaim the form of hinge shown in Ar- 100

nold's Patent No. 590,873, wherein a hinge is shown provided with circular enlargements at its opposite ends and adapted to be clamped between opposing surfaces of grooved boards. 5 My invention is a hinge having sharply-defined angular projections or flanges which get a tenacious grip in the material and prevent any possible wedge-like action under a longitudinal pull of the hinge. My hinge is intended to be driven edgewise into the wood or other material after a proper kerf has been sawed therein to receive the hinge with a driving fit.

Having described my invention, what I 15 claim as new, and desire to secure by Letters Patent, is—

1. As an article of manufacture, a hinge, comprising oppositely - extending leaves united at their adjacent ends by a hinge-pintle, and lying in the plane of the pintle, said leaves being provided with pairs of outturned flanges extending straight out from the plane of the leaves, and presenting at their junction with the body of the leaves a sharp angle less than an obtuse angle, substantially as described.

2. As an article of manufacture, a hinge, having a narrow flange at the opposite extremities of the hinge-leaves, said flanges being parallel to the pintle and flat or plane as distinguished from curved or rolled, and form-

ing with said leaves an angle less than an obtuse angle, substantially as described.

3. As an article of manufacture, a hinge comprising oppositely - extending leaves 35 united at their adjacent ends by a hinge-pintle, and lying in the plane of the pintle, said hinge containing a T-shaped head, substantially as described, whose oppositely-extending flanges form at their junction with the 40 hinge-leaf a sharp angle less than an obtuse angle, substantially as and for the purpose set forth.

4. A hinge having a flange at the extremity of a leaf of said hinge, said flange projecting 45 perpendicularly to the plane of said leaf and forming at its junction therewith substantially a right angle, said flange having at its free end a lateral offset extending rearwardly therefrom at a sharp angle, a depending lip 50 or flange at the free edge of said offset, and a filling-block adapted to fit snugly within and against said projecting flange, offset and depending flange, substantially as described.

In testimony whereof I have signed my 55 name to this specification in the presence of two subscribing witnesses.

JOHN ST. AMAND.
